DRINKING CUP

Bozena Merta, Chicago, Ill.

Application February 14, 1936, Serial No. 63,919

4 Claims. (Cl. 229—1.5)

This invention relates to non-rigid receptacles, cups, or cup liners and more particularly to improved blanks therefor.

It contemplates more especially an improved blank and paper cup construction that is preferably conical in form, more durable in use and possessed of greater self-sustaining characteristics.

Blanks for producing cups of this type are cut from sheets of paper, either plain or paper having waterproofing characteristics, and such blanks are then rolled around a suitable mandrel and the outer overlapping edge is adhesively secured to the body of the blank to secure it in cup-shape formation. Most, if not all, commercial forms of blanks for producing conically shaped cups are non-symmetrical in outline, necessitating careful handling of the blanks in the process of applying the adhesive material to the proper edge 10 of the blank, and in feeding the blanks to the forming mandrel.

One object of the present invention is to provide a novel design of blank of symmetrical outline which permits reversal of the blank.

Another object is to provide a blank having an extension adjacent the apex portion of the cup blank, serving as the means for gripping to facilitate its formation into a cup.

Still another object is the provision of a novel design blank having an extension adjacent the apex portion of the blank serving as the means for gripping to facilitate its formation into a cup, and adapted to be disposed interiorly of and adjacent the apex of the cup.

A further object is the provision of a novel design of blank having two symmetrical extensions adjacent the apex portion of the blank, one serving as the means for gripping in the operation of forming the cup and disposed on the interior 30 apex portion of the cup, and the other overlapping the exterior apex portion of the cup.

A still further object is to provide a cup blank of novel design that is economical for use in forming conical cups, and which results in producing a cup of reinforced construction, having a tightly closed relatively strong apex portion.

Other objects and advantages will appear from the following description of illustrated embodiments of the present invention.

In the drawings:

Figure 1 is a developed plan view of the first form of blank.

Figure 2 is a side view of a cup made from a 55 blank of first form.

Figure 3 is a developed plan view of the improved conical cup blank embodying this invention.

Fig. 4 is a side view of the cup formed from the novel design of blank shown in Fig. 3 embodying the present invention.

Fig. 5 is a top view of the formed cup.

Fig. 6 is a view of the novel design of blank and mandrel for forming it into a cup, showing the blank in the initial position of engagement with the mandrel.

Fig. 7 is a view similar to Fig. 6 showing the final step in the operation of forming the cup.

Figs. 1 and 2 represent the first important development of my invention, the main feature of my conical cup being the highly desirable rigid, strong and overlapping construction of the apex of the finished cup. The blank indicated in this form is designated by reference numeral 1 and is of symmetrical heart shape including two similarly curved edges 2 and 3 joined to form a tip 4, and the opposite ends merge into similarly curved edges 5 and 5a respectively, connected at 6, forming a reentrant angle thereat. The portions 7 and 8, adjacent said edges 5 and 5a, serve as extensions either of which may be gripped in the cone mandrel for forming a cup in a manner herein described. In order that the blank may be secured in cup shape form, an area adjacent one of said edges 2 or 3, depending upon which of the extensions, 7 or 8, is to be gripped by the mandrel, is provided with an adhesive coating 9. Said adhesive area is always located in opposite relation to the extension adapted to be gripped by the mandrel. A cup produced by such a heart shape blank is clearly shown in Figure 2 of the drawings.

The next development in the principles of construction illustrated and described hereinbefore with reference to Figs. 1 and 2 is the form 40 which I will now describe and which differs from the first above mentioned form only in the addition to the blank of Fig. 1 of two substantially triangular wing-like areas, which as a whole, present a blank as shown in Fig. 3.

This form of the cup blank selected for illustration comprises a body portion 10, cut from a sheet of paper, either plain or paper having water-proofing properties. As may be seen in Figure 3 of the drawings the blank is of symmetrical outline, and is defined by an arcuate edge 11, generated about the center 12, and two non-radial straight converging edges 13 and 14 connecting at their upper ends to the arcuate edge 11. Said edges 13 and 14 desirably are lo- 50 55

cated in the same relations to the center 12, and their lower portion each merge into similarly formed curved edges 16 and 17, which meet at or adjacent the center 12, forming a reentrant angle. However, the said edges 13 and 14, may be located at angle to the radius of the arc passing through its outer end, different from the angle formed by the other edge, such as a radial edge, and it will also be seen that the portions adjacent curved edges 16 and 17 need not be of similar size or shape. However, a symmetrical design of blank is preferred since it simplifies handling in the operation of making cups, and permits reversing of the blank, side for side, requiring less care in the operation of applying adhesive, or in the operation of forming the cup.

The lateral portions of the blank designated, 20 and 21, and defined by dot and dash lines 22 and 23, provide the overlapping portions forming the side wall of the cup which serve to provide adequate reinforcement for the entire cup structure. The lower portions of said areas 20 and 21 each include extensions, 24 and 25 respectively, defined by the curved edges 16 and 17. One of said extensions serves as the means for gripping by a mandrel for facilitating the formation of the blank into a cup, and by reason thereof is caused to be disposed interiorly and forming a part of the inner apex portion of the cup, while the other extension is wrapped to form an exterior apex portion of the cup, resulting in producing a tightly closed relatively rigid apex portion of the cup.

The cup may be formed on a mandrel of the type illustrated in Figures 6 and 7 which includes a cone composed of a frusto-conical portion 30, made of metal and a longitudinally movable cone tip 31, which is adapted to grip the extension 25 of the blank preparatory to wrapping the blank around the cone to form the cup. In gripping the extension 25, it is folded long the line indicated at 25a, and the adjustable arm 32, engaging the blank adjacent said fold is caused to wrap the blank around the cone to form the cup. The overlapping outer portion 20, is then adhesively connected to the body of the blank to secure it in cup-shape formation. As may be seen in the drawings the lateral portion of the blank adjacent edge 13 is provided with an area of adhesive indicated at 34, and it may be understood that such adhesive may be applied thereto during the forming operation. It will also be apparent that the cup may be formed by either right or left hand wrapping, and desirably the adhesive is applied to the opposite lateral portion of the blank when extension 24 is to be inserted into the gripper of the mandrel, in forming the cup. The adhesive coated area 34, desirably terminates a short distance from the straight edge 13, so that adhesive will not be pressed out beyond the edge when forming the cup.

A further important feature of my invention is the novel method of forming the cup, this being accomplished by gripping either of the extending portions 24 or 25, the edges of which form the aforesaid reentrant angle, the gripping medium whereof grips such extension substantially along the dotted line indicated in the drawings. The gripping element, preferably of conical shape, rotates to roll the cup into the form indicated in Fig. 4 in such a manner that the gripped extension 24 (or 25) when released, lies firmly against the inside surface of the apex

of the cup to add rigidity and strength thereto, while the opposite extending portion and area 25 and areas adjacent thereto become the outer reinforcing layers of the apex of the cup.

It will be noted that the finished cup or liner such as shown in Figs. 2 and 4 has the apex so formed that portions of the areas adjacent curved edges 5 and 5a overlap each other and that the extending curved portion of the blank 7 forms an exterior overlapping double construction for the apex of the cup giving the same adequate strength, rigidity and body. Further, it will be noted that in the cup construction illustrated in Fig. 2 a portion of the blank comprising extension 8 has been gripped in forming the cup and lies on the inside of the apex interiorly of the cup, this also imparting added rigidity, body and resulting in said extension being held firmly against the wall of the apex by the natural tendency of the paper as well as by the weight of water which may be placed in the cup.

Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

1. A cup of conical form, formed from a blank having an arcuate edge and a pair of straight converging edges merging to form an edge defining a re-entrant angle and terminating substantially at the center of the arc, and having a pair of integral segments on opposite sides respectively of said re-entrant angle, the edges of the segments being rounded, one of the segments forming a reinforcing interior for the apex of the cup, the other of said segments and the adjacent portion of the blank forming an overlapping exterior reinforcing portion for the apex of the cup, said exterior reinforcing portion being adhesively secured to the body of the cup.

2. A cup of conical form, formed from a blank of substantially triangular shape having an arcuate edge and two non-radial straight edges which converge and merge to form a re-entrant angle and terminating substantially at the center of the arc, and having a pair of integral segments on opposite sides respectively of said re-entrant angle, the edges of the segments being rounded, one of said segments having outer edge portion folded to provide a gripping extension to facilitate the formation of the cup, the aforementioned segment forming a reinforcing interior for the apex of the cup, the other segment and the adjacent portion of the blank forming an overlapping exterior reinforcing portion for the apex of the cup, the exterior reinforcing portion having its inner surface provided with an adhesive coating whereby it may be fixedly secured to the body of the cup.

3. The method of forming a conical cup from a blank having an arcuate edge and a pair of non-radial straight converging edges terminating in rounded segments which coact to form a re-entrant angle therebetween, comprising gripping one of the segments on the apex portion of a conical mandrel, thence rolling the blank from said gripped segment around the conical mandrel toward the arcuate edge of the blank, and then in an arcuate path toward the other segmental portion until the last mentioned seg-

mental portion overlaps the apex of the cup, so that the exterior non-parallel blank edge defines an inclined spiral about the cup from the upper edge to the apex at the lower end thereof.

5. The method of forming a conical cup from a blank having an arcuate edge and a pair of non-radial straight converging edges terminating in rounded segments which coact to form a re-entrant angle therebetween, comprising folding one of the segmental portions defining a chord of the rounded edge of said segmental portion, gripping the folded portion of said segment on the apex portion of a conical mandrel, 5
10 thence wrapping the blank through the medium of a wrapping arm from the gripped portion of the aforementioned segment around the conical mandrel toward the arcuate edge of the blank and then in an arcuate path toward the other segmental portion until the last mentioned segmental portion overlaps the apex of the cup, so that the exterior non-parallel blank edge defines an inclined spiral about the cup from the upper edge to the apex at the lower end thereof, 10 and adhesively uniting the overlapping portions of the blank together.

BOZENA MERTA.
